UNITED STATES PATENT OFFICE.

WILLIAM M. WILHELM, OF KALAMAZOO, MICHIGAN.

ROLL-GRINDING MACHINE.

No. 830,550.

Specification of Letters Patent.

Patented Sept. 11, 1906.

Application filed April 22, 1905. Serial No. 256,926.

To all whom it may concern:

Be it known that I, WILLIAM M. WILHELM, a citizen of the United States, and a resident of the city and county of Kalamazoo, State 5 of Michigan, have invented certain new and useful Improvements in Roll-Grinding Machines, of which the following is a specification.

This invention relates to improvements in 10 roll-grinding machines.

The objects of this invention are, first, to provide an improved roll-grinding machine by which rolls of large size may be satisfactorily ground; second, to provide an improved 15 roll-grinding machine by which such rolls as the rolls of paper-making machines may be satisfactorily ground without removing them from the machines; third, to provide an improved roll-grinding machine 20 which may be readily adjusted for grinding rolls of varying diameters; fourth, to provide an improved roll-grinding machine adapted to be adjusted so that it produces the desired crowning of the rolls; fifth, to provide an 25 improved roll-grinding machine which may be quickly adjusted to compensate for the wear of the grinding-wheel; sixth, to provide an improved roll-grinding machine which is 30 comparatively simple in construction, is very durable, and easy to manipulate in use.

Further objects and objects relating to structural details will definitely appear from the detailed description to follow.

I accomplish the objects of my invention 35 by the devices and means described in the following specification.

The invention is clearly defined, and pointed out in the claims.

A structure embodying the features of my 40 invention is clearly illustrated in the accompanying drawings, forming a part of this specification, in which—

Figure 1 is a plan view of my improved roll-grinding machine shown in operative relation with a roll to be ground. Fig. 2 is a 45 side-elevation view of my improved roll-grinding machine. Fig. 3 is an enlarged end elevation of my improved roll-grinding machine, taken from the left of Fig. 1. Fig. 4 50 is an enlarged transverse sectional view taken on a line corresponding to line 4-4 of Figs. 1 and 2. Fig. 5 is a detail plan view showing the support and the means of horizontally adjusting the grinding-wheel, partially in section, on a line corresponding to line 5-5 of Fig. 4. Fig. 6 is a detail vertical sectional

view showing the means for the vertical adjustment of the grinding-wheel, taken on a line corresponding to line 6-6 of Fig. 5.

In the drawings the sectional views are 60 taken looking in the direction of the little arrows at the ends of the section-lines, and similar letters of reference refer to similar parts throughout the several views.

Referring to the drawings, I provide a way 65 preferably made up of longitudinal rails A and cross-pieces A', the rails A being disposed at the corners, forming a rectangular frame. The longitudinal rails are braced at intervals with X-shaped brackets I, as clearly appears 70 in Fig. 4, so that they are firmly and rigidly secured together. The way is further strengthened by the longitudinal truss-rods a' and a''. The truss-rods a', which brace the way laterally, are secured to the brackets 75 a''', which are mounted on the inner faces of the longitudinal rails A. These truss-rods are arranged in pairs, as clearly appears in Figs. 1 and 4. The truss-rods are arranged through the centrally-arranged bracket a, 80 (see Fig. 1,) which forms the truss-block. The truss-rods a'' prevent the horizontal sagging of the way. The way is adjustably supported upon the standards B, which are provided with cross-pieces B', on which it rests. 85 The cross-pieces B' are adjustably secured to the standards by means of bolts b, which are arranged through suitable slots b' in the standard. (See Figs. 2 and 3.) The way is rigidly secured in position upon the cross-pieces by the set-screws b'', which are arranged through the upper ends of the standards and engage the bottom rails A.

A carriage C, adapted to travel upon the way, is provided. This carriage is adapted 95 to rest upon the top rails of the way and is provided with a downward extension at the front, upon which the grinding-wheel is adjustably secured. This downwardly-extending portion of the carriage bears upon the 100 lower inner rail A. The grinding-wheel is supported upon the outwardly-projecting arms C''' of the bracket C''. This bracket C'' is adjustably secured to the carriage C by means of the screws c, which are arranged 105 through suitable slots c', in the bracket, and the set-screws c'', which engage the bottom of the bracket. The set-screws are arranged through suitably-projecting lugs c''' on the carriage. (See Figs. 4 and 6.) By means of this vertical adjustment the grinding-wheel D' may be properly adjusted to bring it to the 110

center of the roll to be ground. The bearings E' for the shaft D of the grinding-wheel are carried by the yoke E, which rests upon the arms C''. This yoke is adjustable horizontally by means of the set-screws e'' and the bolts e, which are arranged through suitable slots e' in the yoke. (See Fig. 5.) By this adjustment the grinding-wheel is brought into proper relation to the roll to be ground. The carriage C is provided with the platform C' upon which an electric motor, as G, is mounted. The motor is connected to the pulley D'' of the grinding-wheel shaft by a suitable belt, as G'. The carriage C is driven by means of the screw bearing-shaft F, which is mounted in suitable bearings F' on the way. The screw-shaft F is provided with a pulley F'' at one end, which is connected by means of a suitable belt to the roll to be ground, as H. (See Fig. 1.) Two belts are shown in the figure to show that the shaft may be driven in either direction in this manner. The carriage C is connected to the driving-shaft by means of the split nut f. (See Fig. 4.) The nut f is thrown into and out of its engaging position by means of the lever f', which is connected to the halves of the nut by the links f'' and f'''. These links are pivoted to the lever on opposite sides of the pivot-point, so that by the operation of the lever both halves of the nut are either thrown together to engage the shaft or apart to release it. By this arrangement the carriage can be disengaged from its driving means or engaged thereto, as desired. This is of advantage, as some portions of a roll may require more grinding than others. By releasing the driving-nut the carriage can be readily reciprocated on the way.

The roll H, in relation to which I have shown my improved roll-grinding machine, is shown in conventional form. It is evident that such rolls as—*e.g.*, those of paper-making machines—may be ground without removing them from the machines.

I have shown my improved grinder mounted upon the standards B. I will state, however, that the way is in some instances mounted directly upon the frame of the paper-making machine. The grinding of the rolls without removing them from the machine is of very great advantage, as these rolls weigh several tons, and when it is necessary to remove them from the machine a large amount of time is consumed further than that necessary for the actual grinding operations. It is also then necessary to provide special mounts therefor. It is necessary in order to secure good results that these rolls be perfectly ground—that is, uniformly ground from end to end. It is therefore necessary that the way be very rigid. Otherwise it is likely to sag or to bow out, which will of course produce undesirable results, as the rolls to be ground are often twelve or fourteen feet in

length. It is sometimes desirable to grind the rolls crowning. I accomplish this by the adjustment of the way, bowing the same out slightly by means of the truss-rods a'. By this means I am enabled to secure the desired crowning and at the same time have the roll uniformly and perfectly ground. By mounting the driving-motor for the grinding-wheel upon the carriage the same is independently driven and without the aid of shafting, which is a very desirable feature.

By arranging the parts as I have illustrated and described I am enabled to accurately adjust the machine to various sizes of rolls in various positions. It may also be quickly adjusted to compensate for the wear of the grinding-wheel in operation.

I have illustrated and described my improved roll-grinding machine in detail in the form preferred by me on account of its structural simplicity and convenience in operation. I am, however, aware that it is capable of considerable variation in structural details without departing from my invention, and I desire to claim the same specifically as illustrated as well as broadly.

Having thus described my invention, what I claim as new, and desire to secure by Letters Patent, is—

1. In a roll-grinding machine, the combination of a way consisting of longitudinal rails secured together by suitable cross-pieces to form a rectangular frame; truss-rods arranged in pairs to truss said way laterally, said truss-rods being provided with adjusting means whereby said way may be bowed; a carriage; a bracket adjustably secured to said carriage; a grinding-wheel; bearings for said grinding-wheel adjustably secured upon said bracket; a screw driving-shaft for said carriage; a divided driving-nut on said carriage; a pivoted lever; links connected to the parts of said nut and to said lever on opposite sides of its pivot-point; an electric motor for driving said grinding-wheel, mounted on said carriage; driving connections for said screw-shaft; a support for said way comprising standards; and cross-pieces adjustably secured to said standards, coacting for the purpose specified.

2. In a roll-grinding machine, the combination of a way consisting of longitudinal rails secured together by suitable cross-pieces to form a rectangular frame; a carriage; a bracket adjustably secured to said carriage; a grinding-wheel; bearings for said grinding-wheel adjustably secured upon said bracket; a screw driving-shaft for said carriage; a divided driving-nut on said carriage; a pivoted lever; links connected to the parts of said nut and to said lever on opposite sides of its pivot-point; an electric motor for driving said grinding-wheel, mounted on said carriage; driving connections for said screw-shaft; a support for said way comprising standards;

and cross-pieces adjustably secured to said standards, coacting for the purpose specified.

3. In a roll-grinding machine, the combination of a way consisting of longitudinal rails secured together by suitable cross-pieces to form a rectangular frame; truss-rods arranged in pairs to truss said way laterally, said truss-rods being provided with adjusting means whereby said way may be bowed; a carriage; a bracket adjustably secured to said carriage; a grinding-wheel; bearings for said grinding-wheel adjustably secured upon said bracket; a screw driving-shaft for said carriage; an electric motor for driving said grinding-wheel, mounted on said carriage; driving connections for said screw-shafts; a support for said way comprising standards; and cross-pieces adjustably secured to said standards, coacting for the purpose specified.

4. In a roll-grinding machine, the combination of a way consisting of longitudinal rails secured together by suitable cross-pieces to form a rectangular frame; a carriage; a bracket adjustably secured to said carriage; a grinding-wheel; bearings for said grinding-wheel adjustably secured upon said bracket; a screw driving-shaft for said carriage; an electric motor for driving said grinding-wheel, mounted on said carriage; driving connections for said screw-shaft; a support for said way comprising standards; and cross-pieces adjustably secured to said standards, coacting for the purpose specified.

5. In a roll-grinding machine, the combination of a way consisting of longitudinal rails secured together by suitable cross-pieces to form a rectangular frame; truss-rods arranged in pairs to truss said way laterally, said truss-rods being provided with adjusting means whereby said way may be bowed; a carriage; a bracket adjustably secured to said carriage; a grinding-wheel; bearings for said grinding-wheel adjustably secured upon said bracket; a screw driving-shaft for said carriage; a divided driving-nut on said carriage; a pivoted lever; links connected to the parts of said nut and to said lever on opposite sides of its pivot-point; an electric motor for driving said grinding-wheel, mounted on said carriage; and driving connections for said screw-shaft, coacting for the purpose specified.

6. In a roll-grinding machine, the combination of a way consisting of longitudinal rails secured together by suitable cross-pieces to form a rectangular frame; a carriage; a bracket adjustably secured to said carriage; a grinding-wheel; bearings for said grinding-wheel adjustably secured upon said bracket; a screw driving-shaft for said carriage; a divided driving-nut on said carriage; a pivoted lever; links connected to the parts of said nut and to said lever on opposite sides of its pivot-point; an electric motor for driving

said grinding-wheel, mounted on said carriage; and driving connections for said screw-shaft; coacting for the purpose specified.

7. In a roll-grinding machine, the combination of a way consisting of longitudinal rails secured together by suitable cross-pieces to form a rectangular frame; truss-rods arranged in pairs to truss said way laterally, said truss-rods being provided with adjusting means whereby said way may be bowed; a carriage; a bracket adjustably secured to said carriage; a grinding-wheel; bearings for said grinding-wheel adjustably secured upon said bracket; a screw driving-shaft for said carriage; an electric motor for driving said grinding-wheel, mounted on said carriage; and driving connections for said screw-shaft, coacting for the purpose specified.

8. In a roll-grinding machine, the combination of a way consisting of longitudinal rails secured together by suitable cross-pieces to form a rectangular frame; a carriage; a bracket adjustably secured to said carriage; a grinding-wheel; bearings for said grinding-wheel adjustably secured upon said bracket; a screw driving-shaft for said carriage; an electric motor for driving said grinding-wheel, mounted on said carriage; and driving connections for said screw-shaft, coacting for the purpose specified.

9. In a roll-grinding machine, the combination of a way; truss-rods arranged in pairs to truss said way laterally, said truss-rods being provided with adjusting means whereby said way may be bowed; a carriage; a grinding-wheel adjustably mounted on said carriage; a screw driving-shaft for said carriage; a divided driving-nut on said carriage; a pivoted lever; links connected to the parts of said nut and to said lever on opposite sides of its pivot-point; driving connections for said screw-shaft; a support for said way, comprising standards; and cross-pieces adjustably mounted on said standards, for the purpose specified.

10. In a roll-grinding machine, the combination of a way; truss-rods arranged in pairs to truss said way laterally, said truss-rods being provided with adjusting means whereby said way may be bowed; a carriage; a grinding-wheel adjustably mounted on said carriage; a screw driving-shaft for said carriage; a divided driving-nut on said carriage; a pivoted lever; links connected to the parts of said nut and to said lever on opposite sides of its pivot-point; and driving connections for said screw-shaft; for the purpose specified.

11. In a roll-grinding machine, the combination of a way; truss-rods arranged in pairs to truss said way laterally, said truss-rods being provided with adjusting means whereby said way may be bowed; a carriage; a grinding-wheel adjustably mounted on said carriage; a screw driving-shaft for said car-

riage; driving connections for said screw-shaft; a support for said way, comprising standards; and cross-pieces adjustably mounted on said standards, for the purpose specified.

12. In a roll-grinding machine, the combination of a way; truss-rods arranged in pairs to truss said way laterally, said truss-rods being provided with adjusting means whereby said way may be bowed; a carriage; a grinding-wheel adjustably mounted on said carriage; a screw driving-shaft for said carriage; and driving connections for said screw-shaft, for the purpose specified.

13. In a roll-grinding machine, the combination of a way; a carriage; a grinding-wheel adjustably mounted on said carriage; a screw driving-shaft for said carriage; a divided driving-nut on said carriage; a pivoted lever; links connected to the parts of said nut and to said lever on opposite sides of its pivot-point; an electric motor for driving said grinding-wheel, mounted on said carriage; driving connections for said screw-shaft; a support for said way, comprising standards; and cross-pieces adjustably mounted on said standards, for the purpose specified.

14. In a roll-grinding machine, the combination of a way; a carriage; a grinding-wheel adjustably mounted on said carriage; a screw driving-shaft for said carriage; a divided driving-nut on said carriage; a pivoted lever; links connected to the parts of said nut and to said lever on opposite sides of its pivot-point; an electric motor for driving said grinding-wheel, mounted on said carriage; and driving connections for said screw-shaft, for the purpose specified.

15. In a roll-grinding machine, the combination of a way consisting of longitudinal rails secured together by suitable cross-pieces to form a rectangular frame; truss-rods arranged in pairs to truss said way laterally, said truss-rods being provided with adjusting means whereby said way may be bowed; a carriage; a grinding-wheel adjustably mounted on said carriage; a screw driving-shaft for said carriage; a divided nut on said carriage; a pivoted lever; links connected to the parts of said nut and to said lever on opposite sides of its pivot-point; an electric motor for driving said grinding-wheel mounted on said carriage; and driving connections for said screw-shaft, for the purpose specified.

16. In a roll-grinding machine, the combination of a way consisting of longitudinal rails secured together by suitable cross-pieces to form a rectangular frame; truss-rods arranged in pairs to truss said way laterally, said truss-rods being provided with adjusting means whereby said way may be bowed; a carriage; a grinding-wheel adjustably mounted on said carriage; a screw driving-shaft for said carriage; an electric motor for driving said grinding-wheel mounted on said carriage;

riage; and driving connections for said screw-shaft, for the purpose specified.

17. In a roll-grinding machine, the combination of a way consisting of longitudinal rails secured together by suitable cross-pieces to form a rectangular frame; a carriage; a grinding-wheel adjustably mounted on said carriage; a screw driving-shaft for said carriage; an electric motor for driving said grinding-wheel mounted on said carriage; and driving connections for said screw-shaft, for the purpose specified.

18. In a roll-grinding machine, the combination of a way consisting of longitudinal rails secured together by suitable cross-pieces to form a rectangular frame; truss-rods arranged in pairs to truss said way laterally, said truss-rods being provided with adjusting means whereby said way may be bowed; a carriage; a grinding-wheel mounted on said carriage; a screw driving-shaft for said carriage; a divided nut on said carriage; a pivoted lever; links connected to the parts of said nut and to said lever on opposite sides of its pivot-point; an electric motor for driving said grinding-wheel mounted on said carriage; and driving connections for said screw-shaft, for the purpose specified.

19. In a roll-grinding machine, the combination of a way consisting of longitudinal rails secured together by suitable cross-pieces to form a rectangular frame; a carriage; a grinding-wheel mounted on said carriage; a screw driving-shaft for said carriage; a divided nut on said carriage; a pivoted lever; links connected to the parts of said nut and to said lever on opposite sides of its pivot-point; an electric motor for said grinding-wheel mounted on said carriage; and driving connections for said screw-shaft, for the purpose specified.

20. In a roll-grinding machine, the combination of a way; truss-rods arranged in pairs to truss said way laterally, said truss-rods being provided with adjusting means whereby said way may be bowed; a carriage; a grinding-wheel adjustably mounted on said carriage; a screw driving-shaft for said carriage; an electric motor for driving said grinding-wheel mounted on said carriage; driving connections for said screw-shaft; a support for said way, comprising standards; and cross-pieces adjustably mounted on said standards, for the purpose specified.

21. In a roll-grinding machine, the combination of a way; truss-rods arranged in pairs to truss said way laterally, said truss-rods being provided with adjusting means whereby said way may be bowed; a carriage; a grinding-wheel adjustably mounted on said carriage; a screw driving-shaft for said carriage; an electric motor for driving said grinding-wheel mounted on said carriage; and driving connections for said screw-shaft, for the purpose specified.

22. In a roll-grinding machine, the combination of a way; truss-rods arranged in pairs to truss said way laterally, said truss-rods being provided with adjusting means whereby said way may be bowed; a carriage; a grinding-wheel mounted on said carriage; a screw driving-shaft for said carriage; an electric motor for driving said grinding-wheel mounted on said carriage; driving connections for said screw-shaft; a support for said way, comprising standards; and cross-pieces adjustably mounted on said standards, for the purpose specified. 30
23. In a roll-grinding machine, the combination of a way; truss-rods arranged in pairs to truss said way laterally, said truss-rods being provided with adjusting means whereby said way may be bowed; a carriage; a grinding-wheel mounted on said carriage; a screw driving-shaft for said carriage; an electric motor for driving said grinding-wheel mounted on said carriage; and driving connections for said screw-shaft, for the purpose specified. 35
24. In a roll-grinding machine, the combination of a way; a carriage; a grinding-wheel mounted on said carriage; a screw driving- 40
- 25
- shaft for said carriage; an electric motor for driving said grinding-wheel mounted on said carriage; driving connections for said screw-shaft; a support for said way, comprising standards; and cross-pieces adjustably mounted on said standards, for the purpose specified.
25. In a roll-grinding machine, the combination of a way; means for bowing said way laterally; a carriage; a grinding-wheel adjustably mounted on said carriage; means for driving said carriage; and an electric motor for driving said grinding-wheel mounted on said carriage, for the purpose specified. 45
26. In a roll-grinding machine, the combination of a way; means for bowing said way laterally; a carriage; a grinding-wheel mounted on said carriage; and means for driving said carriage, for the purpose specified.

In witness whereof I have hereunto set my hand and seal in presence of two witnesses.

WILLIAM M. WILHELM. [L. s.]
